UNITED STATES PATENT OFFICE.

ARTHUR W. BEARDSELL, OF MILFORD, MASSACHUSETTS, ASSIGNOR TO THE DRAPER COMPANY, OF PORTLAND, MAINE, AND HOPEDALE, MASSACHUSETTS.

LOOM.

SPECIFICATION forming part of Letters Patent No. 629,311, dated July 18, 1899.

Application filed April 6, 1899. Serial No. 711,886. (No model.)

To all whom it may concern:

Be it known that I, ARTHUR W. BEARDSELL, of Milford, county of Worcester, State of Massachusetts, have invented an Improvement in 5 Looms, of which the following description, in connection with the accompanying drawings, is a specification, like letters and figures on the drawings representing like parts.

This invention relates more especially to 10 looms provided with automatic filling-supplying mechanism, whereby the shuttle is provided with a fresh supply of filling upon the more or less complete exhaustion of the previous supply or upon its breakage.

15 My present invention has for one of its objects the production of means for controlling the filling-supplying mechanism through two different and independent sets of devices, the one operative upon failure of the filling and 20 the other operative upon the exhaustion of the filling in the shuttle to a predetermined extent.

The loom is provided with stopping means which will be automatically operated upon a 25 second failure of filling to thereby stop the loom, whereas if the filling-supplying mechanism is actuated upon the exhaustion of the filling to a predetermined extent said stopping means will be held inoperative unless a 30 mishread should occur.

I have herein shown a sufficient portion of the filling-supplying mechanism to be understood as substantially that shown in United States Patent No. 529,940, dated November 35 27, 1894, to which reference may be had.

Figure 1 is a perspective view of the left-hand end of the breast-beam and the lay of the loom with one embodiment of my invention applied thereto, the lay being shown as 40 having nearly reached its rearmost position. Fig. 2 is a left-hand side elevation of a portion of the loom shown in Fig. 1 to illustrate the relative position of the filling-supplying mechanism and the controlling means therefor. Fig. 3 is a plan view, on an enlarged scale, of the means governed by the filling-feeler and the filling-fork which coöperate with the controlling means for the filling-supplying mechanism; and Fig. 4 is a side elevation 45 of the mechanism shown in Fig. 3.

It will be supposed that the filling-supplying mechanism will be located at one end of the lay, the latter being cut away at the adjacent shuttle-box to permit the passage therethrough of the ejected-filling carrier from the 55 shuttle, as in the United States patent referred to, said filling-supplying mechanism comprising, essentially, a feeder or hopper F, Fig. 2, and the transfeerer f', (see dotted lines, Fig. 2,) mounted on the stud f and actuated 60 substantially as set forth in said Patent No. 529,940 to transfer a fresh-filling carrier from the feeder to the shuttle at the proper time.

Referring now to Fig. 1, the front plate B¹⁵ of the shuttle-box at the left-hand end of the 65 lay A³ is provided with an upturned bracket b, on which is pivotally mounted a feeler-carrier, shown as an arm b', extended longitudinally in the direction of the length of the lay and weighted at its outer end at b², the opposite or inner end of the arm being bent to form a dog b³, while the weighted end of the feeler-carrier has attached thereto the filling-feeler b⁴, shown as a substantially Ω-shaped member, the free end of which is preferably 75 enlarged to rest upon the filling f⁵ in the shuttle S when the latter is in the shuttle-box. As the diameter of the mass of filling decreases the filling-feeler will at each beat-up 80 of the lay extend further in toward the longitudinal center of the shuttle due to the weighted end b² of the feeler-carrier, and thereby the opposite end or dog b³ will be elevated.

Inasmuch as the filling-feeler must be removed from the path of the shuttle as the latter is thrown, I have provided a lifter, shown as a cam b⁴, formed on the outer end of an arm b⁵, rigidly secured to the frame A of the loom and extended forwardly in such position 90 that as the lay goes back the lifter b⁴ will pass beneath the weighted end of the feeler-carrier, and the inclined face of the cam will lift said arm and the feeler as the lay reaches its rearmost position, so that the feeler will be 95 entirely out of the way of the shuttle.

The usual shipper-handle S⁶ (shown in Fig. 1) moves in the notched holding-plate a⁶⁹, and a knock-off lever b⁶, which normally rests against or adjacent the shipper-handle, is piv- 100

oted to the breast-beam at b^{16} , the free end of the lever being acted upon by the filling-fork mechanism when it is desired to release the shipper-handle and thereby stop the loom.

5 The filling-fork mechanism herein illustrated is substantially that shown in United States Patent No. 529,943, dated November 27, 1894, and comprises a stand b^7 , mounted on the breast-beam A^{40} and provided with a guideway, in which a slide b^9 is adapted to reciprocate, said slide having pivoted at b^{10} a filling-fork b^{12} , the fork having a rearwardly-projecting tail b^{13} , (best shown in Fig. 4,) adapted to be engaged by a hook b^{14} , pivotally mounted on the upper end of the slide-actuator or weft-hammer A^{19} when the filling is absent as the lay beats up. A latch d^5 is pivoted at d^4 on the slide b^9 , said latch having on its under side a cam 12, the free down-turned end of the latch being adapted to at times operate the knock-off lever b^6 , a pin or stud d^6 , herein shown as mounted on the stand b^7 , having its upper end inturned, as at 14, (see dotted lines, Fig. 3,) to extend beneath 20 and coöperate with the latch-cam 12. Back of the cam 12 the latch is recessed in its side, as at 40, Fig. 4, to receive the inturned end 14 of the pin d^6 when the slide b^9 has been moved outwardly.

30 On the outer side of the slide b^9 I have mounted a rocking bunter m , pivoting it for convenience on the weft-fork pivot b^{10} , said bunter having a forwardly-extended finger m' , which is normally held by the weight of 35 the depending bunter against one end of an S-shaped arm or detent n , pivoted at n' on the slide, the other upturned end of the detent being notched or recessed to form a shoulder n^2 .

40 The tail b^{13} of the filling-fork forms one connection between the weft-hammer A^{19} and the slide b^9 , the position of said tail or connection being determined by the presence or absence of filling in the shed as the lay comes forward; 45 but in addition to this connection I have provided an independent connection between the slide and the weft-fork, shown as an outwardly-extended loop-like catch o , preferably of stout or heavy wire, with its ends outwardly pivoted, which enter holes in the slide, the catch o , as shown in Fig. 3, being made wide enough to prevent interference with the weft-fork tail b^{13} . One pivot end of the catch, as O' , is extended beyond 55 the side of the slide and is bent forward to form an arm o^2 outside of the S-shaped detent n , said arm at its free end being upturned and bent inward, as at o^3 , to be normally engaged by the shoulder n^2 of the detent, as shown clearly in Figs. 3 and 4. A weight o^4 is secured to the arm o^2 near its free end to prevent disengagement of the end of said arm and the detent by the jarring of the loom or other accidental cause.

65 The lower extremity of the bunter m is normally above the path of movement of the dog b^3 as the latter comes forward when the lay

beats up; but as the filling in the shuttle diminishes the dog is gradually elevated until when the filling has been exhausted to a pre-determined amount the said dog will be elevated sufficiently to engage the depending end of the bunter on the forward movement of the lay, swinging the bunter to the right, Fig. 4, and thereby rocking the S-shaped detent n to withdraw the shoulder n^2 from the overhanging part o^3 of the catch o . This disengagement permits the weight o^4 to drop, and thereby turns the catch o on its pivot into position to be engaged by the hook of the weft-hammer or actuator, so that on the next outward movement of the latter the slide b^9 will be moved outwardly, and its outer end will at such time engage an upturned arm d^{20} , fast on the rock-shaft d' , turning the latter sufficiently to operate the filling-supplying mechanism in well-known manner to thereby insert a fresh supply of filling into the shuttle before complete exhaustion of the filling then in the shuttle. When the shuttle enters the box at the right-hand end of the lay, the feeler will dip down in the empty shuttle-box sufficiently to raise the dog above the depending end of the bunter m , the said bunter, as best shown in Figs. 2 and 4, being rearwardly curved to leave a clear space between its pivotal point and its depending end, so that when the dog is elevated by the descent of the filling-feeler into the empty shuttle-box said dog will enter the clear space between the ends of the bunter and will not engage the latter. When the filling fails, however, the fork b^{12} will not be tilted, and its tail b^{13} will be engaged by the hook of the actuator A^{19} to thereby move the fork-slide outwardly, such outward movement of the slide disengaging the cam 12 of the latch d^5 from the end 14 of the stud or pin d^6 , and the latch will drop behind the knock-off lever b^6 and stop the loom before there has been a thin place or streak made 100 in the cloth. On the inward movement of the slide the cam 12 rides up over the end 14 of the pin, and thus raises the latch into normal position.

When the filling-feeler is made operative 115 to effect a change of filling, the loom must not be stopped unless there be a mistread, and in the latter case the filling will not be laid in the shed, and the filling-fork will then operate as before described, and the loom 120 will be stopped before the formation of a thin place in the cloth. It is thus necessary to prevent stopping of the loom on the outward movement of the slide b^9 when the filling-supplying mechanism is operated by or 125 through the feeler-governed mechanism, and to prevent such stoppage I have herein provided a trip to engage and prevent movement of the latch d^5 into operative position, so that instead of stopping the loom on the outward movement of the fork-slide the filling-supplying mechanism will be operated.

The latch is provided with a laterally-extended pin d^{10} , adapted to be engaged by the

trip c , shown as a plate mounted on the side of the slide b^9 by means of a headed pin c^x , extended through an inclined slot c' in the plate, so that when the latter is moved to the right, viewing Fig. 4, it will also move upwardly and into position to engage the stud d^{10} to thereby prevent the outer end of the latch from descending sufficiently to engage the knock-off lever b^6 . The trip c is connected 10 by a link c^2 with a bell-crank lever c^3 , pivoted at c^4 on the slide b^9 , the opposite arm of said lever being connected by a link c^5 with the depending weight o^x on the arm o^3 of the catch. When the catch o is released, as has been described, and swings downward, the bell-crank lever will be swung on its pivot to move the link c^2 in the direction of the arrow 30, Fig. 4, to thereby move the trip into the operative position described.

20 I have provided means to automatically set the catch o after it has been released by the detent, said setting device being shown as a weighted arm h , pivoted at h' to the slide-stand b^7 and having its upper end oppositely beveled, as at 3. Supposing the catch to have been released, the weight o^x will wipe over the upper end of the arm h on the outward movement of the slide, rocking said arm to permit such passage; but on the return or 30 inward movement of the slide the rocking of the arm h is limited by a pin h^x , so that the weight must ride up over the beveled end of the arm, and as it is so lifted it restores the part o^3 of the catch to its position on the shoulder n^2 of the detent.

35 The controlling means for the filling-supplying mechanism includes for the purposes of this present invention the slide b^9 , the arm d^{20} , and rock-shaft d' , and the usual connections between said rock-shaft and the trans- 40 ferrer, substantially as in the Patent No. 529,940 referred to, and this controlling means is governed by the filling-fork and co-operating devices or by the filling-feeler and its co- 45 operating devices hereinbefore described.

It will be manifest that if the fresh supply 50 of filling is placed in the shuttle upon the exhaustion of the previous supply of filling to a predetermined extent the filling-fork will operate in usual manner should there be a misthread, and the loom will be stopped by the outward movement of the slide, as the trip c is then in normal position, just as is the case when a filling fails.

55 Neither set of devices for governing the controlling means for the filling-supplying mechanism interferes with the other, but each operates properly within its own bounds.

By the construction herein described it is 60 unnecessary to provide for very fine adjustment of the let-off and take-up mechanisms, as such mechanisms are stopped when the loom is stopped upon failure of the filling to be laid in the shed either by reason of failure of the filling or a misthread after a new supply of filling has been transferred to the shuttle.

Having described my invention, what I claim, and desire to secure by Letters Patent, is—

70

1. In a loom, a shuttle containing a supply of filling, filling-supplying mechanism, controlling means therefor including a slide, a filling-fork and a catch independently mounted on the slide, a weft-hammer adapted to move said slide, by or through the fork upon failure of the filling, and to move the slide by engagement with the catch upon predetermined exhaustion of the filling, a feeler to determine the volume of filling in the shuttle, 80 and a governing device for the catch, operative by or through the feeler to cause engagement of the catch and weft-hammer.

2. In a loom, a shuttle containing a supply of filling, filling-supplying mechanism, controlling means therefor including a slide, a weft-hammer, independent and normally inoperative devices mounted on said slide to be engaged singly by the weft-hammer to thereby move the slide, and independent govern- 85 ing means for said devices, the one operative by or through failure of the filling, and the other upon predetermined exhaustion of the filling in the shuttle, whereby the slide will be actuated to effect the operation of the fill- 90 ing-supplying mechanism only upon such predetermined exhaustion of filling in the shuttle.

3. In a loom, a shuttle carrying an exposed supply of filling, filling-supplying mechanism, controlling means therefor, including a slide, a filling-fork mounted thereon, a weft-hammer provided with a hook and adapted to move said slide upon detection of filling failure by the fork, a feeler to intermittently 100 contact with and determine the volume of filling in the shuttle, a normally inoperative catch mounted on the slide, and a governing device for said catch movable with the slide, operative by or through the feeler upon pre- 105 determined exhaustion of the filling in the shuttle, to cause engagement of the catch and weft-hammer and thereby effect the operation of the filling-supplying mechanism.

4. In a loom, a shuttle containing a supply 110 of filling, filling-supplying mechanism, controlling means therefor including a slide, a weft-hammer, independent and normally inoperative devices mounted on said slide to be engaged singly by the weft-hammer to thereby move the slide, and independent govern- 115 ing means for said devices, the one operative by or through failure of the filling, and the other upon predetermined exhaustion of the filling in the shuttle, whereby the slide will be actuated to effect the operation of the fill- 120 ing-supplying mechanism, combined with means to automatically reset the governing means which has been operated by or through exhaustion of the filling.

5. In a loom, stopping means, a shuttle containing a supply of filling, filling-supplying mechanism, controlling means therefor including a slide, movement of the latter due to

130

filling failure effecting the operation of the stopping means, an actuator for the slide, independent and normally inoperative devices to effect coöperation of said slide and its actuator, and governing means for each device, the one operative upon filling failure and the other upon predetermined exhaustion of the filling in the shuttle, combined with a trip controlled by the latter governing means to prevent actuation of the stopping means by operative movement of the slide after filling exhaustion.

6. In a loom, stopping means, a shuttle containing a supply of filling, filling-supplying mechanism, controlling means therefor including a slide, movement of the latter due to filling failure effecting the operation of the stopping means, an actuator for the slide, independent devices to effect coöperation of the slide and actuator, and governing means for each device, the one including a filling-fork and the other including a filling-feeler operative upon predetermined exhaustion of the filling in the shuttle, combined with a trip operated by or through the filling-feeler to prevent actuation of the stopping means by operative movement of the slide after filling exhaustion.

7. In a loom, the lay, a gravity-controlled filling-feeler pivotally mounted thereon, a lifter to move the feeler out of range of the shuttle when the latter is thrown across the lay, a dog connected with the feeler, filling-supplying mechanism, controlling means therefor including a slide, a catch mounted on the slide, a weft-hammer, a detent normally maintaining the catch out of the path of the weft-hammer, and means intermediate said detent and the dog, actuated by the latter to move the detent and release the catch when the filling in the shuttle is exhausted to a predetermined extent.

8. In a loom, the lay provided with a shuttle-box, a gravity-controlled carrier mounted on the lay adjacent the shuttle-box and provided with a dog, a feeler on said carrier to coöperate with and determine the quantity of filling in the shuttle, a lifter to engage said arm and lift the feeler when the shuttle is thrown, filling supplying mechanism, controlling means therefor including a slide, the weft-hammer, means to operatively connect it with the slide, to move the latter, and a governing device for said connecting means, operated by or through the dog when the filling in the shuttle is exhausted to a predetermined point.

9. In a loom, the lay provided with a shuttle-box, a gravity-controlled filling-feeler pivotally mounted on the lay adjacent the shuttle-box and having a connected dog, filling-supplying mechanism, controlling means therefor including a slide, a loop-like catch mounted on the slide, a weft-hammer provided with a hook adapted to at times engage the catch and move the slide, a detent to normally maintain the catch in inoperative posi-

tion, and a rocking bunter to trip the detent, the dog being moved into position to engage and rock the bunter when the filling in the shuttle has been exhausted to a predetermined extent.

10. In a loom, the lay provided with a shuttle-box, a gravity-controlled filling-feeler pivotally mounted on the lay adjacent the shuttle-box and having a connected dog, filling-supplying mechanism, controlling means therefor including a slide, a loop-like catch mounted on the slide, a weft-hammer provided with a hook adapted to at times engage the catch and move the slide, a detent to normally maintain the catch in inoperative position, and a rocking bunter to trip the detent, the dog being moved into position to engage and rock the bunter when the filling in the shuttle has been exhausted to a predetermined extent, combined with means to automatically set the catch in engagement with the detent after operation of the filling-supplying mechanism has been effected.

11. In a loom, the lay provided with a shuttle-box, a filling-carrier pivotally mounted on the lay adjacent the shuttle-box and weighted at one end, a filling-feeler attached to the weighted end of said carrier, to intermittently engage the filling in the shuttle, a fixed lifting-cam to engage and lift the weighted end of the carrier as the lay goes back, filling-supplying mechanism, controlling means therefor, including a slide, a vibrating actuator, a normally inoperative connection between the actuator and the slide, and a governing device for said connection operated by engagement with the free end of the feeler-carrier when the filling in the shuttle has been exhausted to a predetermined extent.

12. In a loom, the lay, a feeler mounted thereon to intermittently coöperate with the filling in the shuttle, filling-supplying mechanism, controlling means therefor, including a slide, a weft-fork on the slide, a vibrating actuator, a catch carried by said slide and adapted to at times be engaged by the actuator to move the slide, a detent for the catch, and means operated by or through the feeler when the supply of filling in the shuttle is exhausted to a predetermined extent, to release the catch and permit the actuation of the slide by its actuator.

13. In a loom, stopping means, a shuttle containing a supply of filling, filling-supplying mechanism, controlling means therefor including a slide, a normally inoperative latch thereon, means to release the latch, movement of the slide due to filling failure releasing the latch and operating the stopping means by or through said latch, an actuator for the slide, independent devices to effect coöperation of the slide and the actuator, governing means for each device, the one including a filling-fork, and the other including a filling-feeler operative upon predetermined exhaustion of the filling in the shuttle, and a trip operated by the filling-feeler to engage and move the

latch into inoperative position and thereby prevent actuation of the stopping means by operative movement of the slide after filling exhaustion.

5 14. In a loom, stopping means, a shuttle containing a supply of filling, filling-supplying mechanism, controlling means therefor including a slide, a normally inoperative latch thereon, means to release the latch, movement 10 of the slide due to filling failure releasing the latch and operating the stopping means by or through said latch, an actuator for the slide, independent devices to effect coöperation of the slide and the actuator, governing means 15 for each device, the one including a filling-fork, and the other including a filling-feeler operative upon predetermined exhaustion of

the filling in the shuttle, a trip operated by the filling-feeler to engage and move the latch into inoperative position and thereby prevent 20 actuation of the stopping means by operative movement of the slide after filling exhaustion, and means to automatically set the trip there-after in normal position and restore to normal position the governing means which includes 25 the filling-feeler.

In testimony whereof I have signed my name to this specification in the presence of two subscribing witnesses.

ARTHUR W. BEARDSELL.
